UNITED STATES PATENT OFFICE.

THOMAS L. DUNBAR AND AUGUST F. RICHTER, OF WATERTOWN, NEW YORK, AS
SIGNORS TO CHEMIPULP PROCESS INC., OF WATERTOWN, NEW YORK.

METHOD AND APPARATUS FOR DIGESTING FIBROUS MATERIAL.

Application filed December 12, 1927. Serial No. 239,488.

This invention relates to improvements in the processes and apparatus for digesting fibrous material, such as wood chips and the like.

5 The primary object of the invention is to improve the systems heretofore known in such manner that the heat units contained in the exhaust gases, may be more effectively utilized, and the gases themselves may be 0 absorbed and thus saved.

Another object of the invention is to provide a process in which the high pressure gases released from the digesters may be introduced into an accumulator tank, and in 5 which the low pressure gases may be introduced either into said accumulator or into a siphonic system, through which fresh liquor from a source of supply is circulating.

Another object is to furnish a system in 0 which gas from the accumulator may be vented under its own pressure into one or more of the digesters when the pressure in the latter is below that of the accumulator.

A still further object is to provide a system in which the gas from the accumulator may be forced by a pump or the like, into one or more of the digesters, for the purpose of creating a pressure in the digesters to expedite penetration of the material undergoing treatment, and also for the recovery of the heat units and the SO_2 contained in the gas.

A further object is to furnish an apparatus including a gas mixer siphon arranged at an elevation above the acid supply and communicating with the latter by means of an unobstructed drop leg pipe extending to the bottom portion of the acid supply tank; said siphon being connected by a conduit to the acid tank, and a pump being arranged in this 0 conduit for forcing acid liquor from the supply tank to the drop leg pipe. A passageway connects the siphon with the digester, so that liquor flowing through the siphon will, when the pressure in the digester has fallen sufficiently, create a suction which will be imparted to the digester for withdrawing gas from the latter.

With the foregoing objects outlined and with other objects in view which will appear 0 as the description proceeds, the invention

consists in the novel features hereinafter described in detail, illustrated in the accompanying drawings, and more particularly pointed out in the appended claims.

Referring to the drawings,

Fig. 1 is a plan view of the improved apparatus with which the new process is carried out, certain parts of the apparatus being omitted to facilitate illustration.

Fig. 2 is a vertical sectional view taken on line 2—2 of Fig. 1.

Fig. 3 is a similar view taken on line 3—3 of Fig. 1.

Fig. 4 is a transverse vertical sectional view, taken on line 4—4 of Fig. 1.

Fig. 5 is a sectional view, taken on line 5—5 of Fig. 1.

In the drawings, 1 designates digesters having cover plates 2. Each digester is provided at its top with a high pressure release 70 branch 3; all of these branches being connected to a common high pressure outlet pipe 4.

Low pressure branch pipes 5 are also connected to the tops of the digesters, and these 75 pipes are connected to a common low pressure line 6. Suitable valves 7 are arranged in the branch pipes to control the passage of release gases from the digesters into the pipes 4 and 6.

Each digester also has a side relief branch 80 8 which is connected to the digester at a point some distance below the top of the same, and these branch pipes are connected to a side relief line 9. A valve 10 is provided for 85 each of the side relief branches.

The pipes 4, 6 and 9 are connected by valved conduits 11, 12 and 13, to a manifold pipe 14, which is connected by a pipe 15 to the lower part of a pressure accumulator tank 90 or chamber 16.

Pipes 11, 12 and 13 are also connected by valved pipes 17, 18 and 19 to a conduit 20 which has a downwardly extending portion connected at its lower end to the side of a 95 mixing siphon or injector 21. The latter has an unobstructed drop leg 22 which discharges into the acid supply tank 23 or the like. The lower end of this drop leg is sealed by the liquor in the tank.

Liquor is withdrawn from the tank by means of a pump 24 which forces the liquor through a pipe 25, which communicates at point 26 with a conduit 27 that is connected to the siphon 21.

When the pump 24 is in operation, liquor will be forced through the pipe 25, and down through the conduit 27, siphon 21 and drop leg 22. Consequently, a suction will be created in the pipe 20, and this suction may be utilized to draw gas, vapor or liquid from the digesters through the pipes 4, 6 and 9.

The pipe 25 is also connected at point 26 to a conduit 28 connected to the upper portion of the accumulator 16. When suitable valves in the pipes are properly manipulated, the pump 24 may be used to force liquor from the tank 23, either to the siphon or to the accumulator.

The lower portion of the accumulator is connected by a pipe 29 to branches 30 leading to the lower ends of the digesters, and a pump 31 is arranged in the line 29 to force heated liquor from the accumulator into one or more of the digesters.

As is usual in such systems, a steam line 32 is used to supply steam to the digesters, but in the present invention, this line is connected by valved branch pipes 33 to injectors 34, through which the steam passes on its way into the digesters.

We may utilize the force of this steam to cause the injectors to exert suction in valved branch pipes 35, which are connected by a line 36, and pipe 37 to the top of the accumulator, whereby gas may be withdrawn from the accumulator by means of the steam injection, and may thus be introduced into the digesters for recovering the heat units of the gas, and for utilizing the SO₂ within the digesters, and creating a balanced pressure on the accumulator.

We also connect the pipe 37 by means of valved branches 38 to the sides of the digesters, so that gas from the accumulator may be fed directly into one or more of the digesters, either under the pressure existing in the accumulator when conditions so permit, or under super-imposed pressure such as can be created by a pump 39 which is connected to the pipe 37 by valved by-pass pipes 40 and 41.

If preferred, the passage of the gas from the accumulator to the digesters may be controlled automatically. For example, the pipe 37 may be provided with a pressure operated valve 42 which will be actuated by pressure existing in the accumulator. When this valve operates, it will, through linkage 43 and 44, operate the valve 45 in the line 36, so that the gases from the accumulator may be automatically fed to the branch pipes 35 leading to the steam injectors.

In the operation of this system, one or more of the digesters is or are charged with chips, and the digester or digesters filled with

pre-conditioned heated acid liquor. Steam is then fed from the pipe 32 into this or these digesters, and this heats the interior of the digester and causes delignification of the fibres.

When the pressure has reached a certain point the valves in the branch pipes 3 are opened, and this permits the gases and vapors released, to flow through the pipe 4, preferably into the accumulator by way of pipe 15. At this time, the accumulator is partially filled with acid liquor, and the hot gases from the digesters heats the liquor in the accumulator, and the SO₂ in the gas is absorbed by the liquor.

During the cooking, the pressure in the accumulator will increase, and in order to relieve the same, the gas and vapor from the accumulator may be vented through pipe 37. From this pipe, it may be fed through the injectors 34 directly back into the digesters from which it originated, or into one of the other digesters.

On the other hand, where conditions will so permit, this gas may be fed through one or more of the branches 38, directly into the sides of the digesters. If the pressure in the accumulator is insufficient to force the gas through the branches 38, the pressure may be increased by passing the gas through the pump 39.

Our system also includes a valved conduit 50 which connects the upper portion of the accumulator to the siphon 21, so that gases from the accumulator may be directly mixed with liquor passing through the siphon for the purpose of pre-conditioning the acid liquor and absorbing the gas.

After the cooking has advanced in the digester to a certain point, the side relief branch 8 may be opened to permit the excess liquor in the digester to discharge from the same. This liquor will pass into the line 9, and from this line, through suitable pipes to the manifold 14. From the latter, it may flow through the pipe 15, directly to the accumulator, or if so desired, it may be passed by way of pipes 11 and 19, to the pipe 20, which will lead the same to the siphon 21, in which it may be mixed with the liquor flowing to the siphon for the purpose of pre-conditioning the liquor and utilizing the heat units and SO₂ contained in the side relief branch liquid.

By means of our system, we can utilize the pressure existing in a digester for automatically feeding gases, vapor and liquid from the digester into the accumulator for pre-conditioning and heating liquor in the accumulator, and as soon as the pressure in the digester has reached a point where it is equal to the pressure existing in the accumulator, the gases may then be withdrawn from the digester by suction from the siphon 21. For example, at the time the low pressure gas and vapor is released, it may flow through the

branches 5 and pipe 6, into the pipes 13 and 17, which leads the same to the pipe 20 which is connected to the siphon 21. Due to this feature of the invention, all of the heat units 5 and SO_2 in the gases and vapors may be utilized, and consequently, the liquor may be pre-conditioned and its temperature may be considerably raised before it is introduced into one of the digesters.

10 When the gas from the accumulator is fed through the pipe 37 and branch 38, into the digester, previous to steaming of the latter, the gas will exert pressure on the acid liquor for causing the liquor to more thoroughly 15 penetrate the material undergoing treatment, which has a distinct advantage in hastening the delignification of the fibrous material, thereby creating a superior product.

By our method we can carry any desired 20 pressure in the accumulator tank, before continuously or intermittently relieving from same. Our usual method of operation is to set our regulating pressure valve on the accumulator at 35 lbs. when we have a working 25 pressure on the digesters of 60 to 65 lbs.

However, if we carry a working pressure 30 on the digesters of from 70 to 75 lbs., which we do for certain grades of pulp, we set our pressure regulating valve or accumulator to release at from 40 to 45 lbs. pressure. And under such circumstances, the temperature 35 under normal operating conditions, may go up to 230° Fahrenheit, and on special tests, it ran up to 260° .

35 From the foregoing, it is believed that the construction, and operation of the apparatus, and the working the process may be clearly understood, and we are aware that changes 40 may be made in the details disclosed without departing from the spirit of the invention as expressed in the claims.

What we claim and desire to secure by Letters Patent is:

1. In the treatment of fibrous material, 45 digesting said material with acid liquor, utilizing the high pressure existing in the digester during a portion of the cooking period for discharging heated high pressure gas and vapor from the digester during that portion 50 of the cooking period and for introducing the same in its heated condition into acid liquor in an accumulator, exerting suction on the digester during another portion of the cooking process to withdraw heated low pressure gases and vapors from the digester, contacting these low pressure gases and vapors while in their heated condition with a flowing stream of acid liquor, and utilizing acid liquor thus preconditioned, from the accumulator 55 and flowing stream, for digesting fibrous material.

2. In the treatment of fibrous material, 60 cooking such material with acid liquor, releasing high pressure gas from the digester and introducing the same under its own pres-

sure into acid liquor in an accumulator, releasing low pressure gas from the digester, mixing the low pressure gas with a flowing stream of acid liquor, and subsequently feeding the last mentioned acid liquor into the ac- 70 cumulator.

3. In the treatment of fibrous material, digesting said material with acid liquor under heat and pressure, releasing high pressure gas and vapor from the digester, and introducing 75 the same in heated condition into acid liquor in an accumulator for heating the liquor and absorbing the gas, releasing low pressure gas and vapor from the digester and mixing the same in heated condition with a 80 flowing stream of acid liquor, subsequently feeding the last mentioned acid liquor into the accumulator and utilizing said acid liquor from the accumulator in its heated condition for digesting fibrous material. 85

4. In the treatment of fibrous material, digesting the material with acid liquor under heat and pressure, releasing high pressure gas and vapor under their own pressure from the sphere of digestion during a portion of 90 the digesting period, and introducing this high pressure gas and vapor in heated condition into acid liquor, exerting suction during another portion of the digesting period for withdrawing low pressure gas and vapor 95 from the sphere of digestion, introducing said low pressure gas in heated condition into acid liquor, and utilizing acid liquor thus preconditioned for digesting fibrous material. 100

5. In the treatment of fibrous material, with acid liquor under heat and pressure, releasing high pressure gas and vapor from the sphere of digestion during a portion of the digesting period, and introducing said 105 gas and vapor in heated condition and under their own pressure into acid liquor, exerting suction during another portion of the digesting period for withdrawing low pressure gas and vapors from the sphere of digestion, introducing said low pressure gas and vapor in heated condition into acid liquor, and utilizing said acid liquor thus heated for digesting fibrous material. 110

6. In the treatment of fibrous material, digesting said material with acid liquor under heat and pressure, releasing high pressure gas and vapor from the sphere of digestion during a portion of the digesting period, and introducing said gas and vapor in heated condition and under their own pressure into a batch of chemical liquor arranged in an accumulator chamber, exerting suction during another portion of the digesting period for withdrawing low pressure gas and vapor 120 from the sphere of digestion, mixing said low pressure gas and vapor in their heated condition with a flowing stream of acid liquor, and then feeding said stream of acid liquor into said accumulator chamber. 125

7. A process for recovering the heat units in the exhaust gas and vapor from a digester, and for reclaiming the SO_2 contained in said gas and vapor, consisting in releasing high pressure gas and vapor from a digester during a portion of the digesting period, and introducing the same under their own pressure and in heated condition, into acid liquor, exerting suction on the digester during another portion of the digesting period, and thus withdrawing low pressure gas and vapor from the digester, introducing said low pressure gas and vapor in their heated condition, into acid liquor, and utilizing the acid liquor thus heated for cooking fibrous material.

8. In the treatment of fibrous material, utilizing hot gas and vapor from a digester for heating acid liquor in an accumulator and also in a pipe line and for absorbing the SO_2 in the gas and vapor by said liquor, feeding the acid liquor from the pipe line into said accumulator, releasing gas and vapor from the accumulator, and introducing said gas into digesting means at different elevations.

9. In the treatment of fibrous material, releasing gas and vapor from a digester and utilizing said gas and vapor for heating acid liquor in an accumulator and also in a pipe line, feeding the acid liquor from the pipe line into said accumulator, and releasing gas and vapor from the top of the accumulator and introducing the same into a digester at a point above the bottom of the latter.

10. In the treatment of fibrous material, releasing gas and vapor from a digester and introducing the same into a batch of acid liquor for heating the latter, and absorbing the SO_2 from the gas and vapor, releasing gas from said batch of liquor, mixing said gas with steam, and introducing the same into a digester.

11. In the treatment of fibrous material, digesting the material with acid liquor, releasing gas and vapor from the digester and introducing the same into a pool of acid liquor in an accumulator, introducing steam into a digester, and utilizing the force of the steam to withdraw gas and vapor from the accumulator, and to feed the same into a digester.

12. In the treatment of fibrous material, withdrawing gas and vapor from a digester and introducing the same into acid liquor contained in an accumulator, withdrawing gas and vapor from the accumulator, superimposing pressure on the gas and vapor from the accumulator and utilizing this superimposed pressure to force said gas into a digester while the latter is undergoing cooking.

13. In the treatment of fibrous material, circulating a stream of acid liquor in an endless path causing said liquor in a part of said endless path to flow by gravity through an unobstructed drop leg passageway, utilizing

force created by the circulation of the liquid for withdrawing low pressure gas and vapor from a digester during cooking of the latter, mixing this gas and vapor with the circulating liquid to heat the liquor and absorb the gas, also releasing high pressure gas and vapor from the digester under the pressure existing in the latter during a part of the cooking period, feeding said high pressure gas and vapor in heated condition into acid liquor in an accumulator, also feeding pre-conditioned acid liquor from said stream into the accumulator, and utilizing heated acid liquor from the accumulator for digesting fibrous material.

14. In an apparatus for treating fibrous material, a digester, an accumulator, means for introducing acid liquor into the accumulator, means for leading gas and vapor from the digester into the accumulator, means for circulating acid liquor in an endless stream, and means for feeding gas and vapor from the digester into the last mentioned means for heating the flowing stream of liquid.

15. In an apparatus for treating fibrous material, a digester, an accumulator tank, means for introducing acid liquor into said tank, a conduit for feeding gas and vapor from the digester to the accumulator, means for moving a stream of acid liquor in an endless path, said last mentioned means including an injector, and a passageway placing the injector in communication with the digester for feeding gas and vapor from the digester to the injector.

16. An apparatus for treating fibrous material, comprising a digester, an accumulator, a gas and vapor conducting pipe connecting the digester and accumulator, a conduit for discharging gas and vapor from the digester, a siphon connected to said conduit, means for feeding acid liquor to said siphon, and an unobstructed hollow drop leg connected to the siphon.

17. In an apparatus of the character described, an accumulator tank, a digester, and a pipe connecting the upper portion of the accumulator to the digester above the bottom of the latter for introducing gas from the accumulator into the digester.

18. In an apparatus of the character described, a digester, means for introducing steam into said digester, an injector forming part of said means and actuated by the steam, an accumulator to contain heated acid liquor, and a conduit connecting the upper end of the accumulator to said injector for utilizing the force of the steam to withdraw gas from the accumulator.

19. In an apparatus of the character described, a digester, an accumulator, a conduit for feeding gas from the accumulator into the digester, above the bottom of the latter, and a pump interposed in said conduit.

20. An apparatus of the character de-

scribed, including a digester having a high pressure relief branch, a low pressure relief branch, and a side relief branch, an accumulator means, means for circulating acid liquor in an endless path, conduits connecting the branches to said means to permit gas, vapor and liquid from the digester, to be fed

to the accumulator means, or to the means for circulating the liquor, a pipe for releasing gas and vapor from the accumulator, and a 10 passageway placing said pipe in communication with the digester.

THOMAS L. DUNBAR.
AUGUST F. RICHTER.
